AUTOMOBILE DOOR STRUCTURE

August L. Nelson, Grand Rapids, Mich., assignor
to Hayes Manufacturing Corporation, Grand
Rapids, Mich., a corporation of Michigan

Application December 28, 1950, Serial No. 203,080

2 Claims. (Cl. 296—44)

1

This invention relates generally to doors, and refers more particularly to improvements in sheet metal door structure.

Although it will be apparent from the following description that many of the features of this invention are applicable to the manufacture of doors for various purposes, nevertheless, the invention finds particular utility when employed in the production of vehicle body doors.

It is an accepted fact that vehicle body doors must possess exceptional rigidity in order to withstand the severe stresses imparted to the doors in practically all directions during use of the vehicle. In the past reasonably satisfactory strength characteristics were obtained by forming the door with separate inner and outer panels secured together by a frame structure interposed between the panels. This construction, however, embodies a relatively large number of parts which not only increase the weight of the door, but in addition, are costly to manufacture and assemble.

With the above in view, it is an object of this invention to greatly simplify the door structure and at the same time provide a door assembly possessing the requisite strength characteristics. In accordance with this invention the door structure is simplified by providing a one-piece sheet metal panel having the marginal edge portions turned laterally and shaped to form the top, bottom and side stiffening rails. These rails being integral with the panel eliminate the complicated, time-consuming assembly operations required in the past where separate framing was used to stiffen the panel and also eliminate the necessity of separately forming the frame members.

Also in accordance with this invention the inner panel employed in the past is replaced by an accessory supporting plate, which is only a fraction of the size of the usual inner door panel, and is secured at opposite ends to the side rails or inturned flanges at opposite sides of the outer door panel. Thus a saving in material is not only effected but the overall weight of the door is reduced. Also repair of the outer door panel in the event the same should become damaged is simplified.

It is a further object of this invention to provide a door structure of the above general type having a window opening in the upper portion. The top of the window opening is defined by the header rail on the panel and opposite sides of the opening are defined by the upper portions of the side rails on the panel. A filler strip extends along the top and sides of the window opening, and opposite edges of the strip are re-

2

spectively secured to inturned flanges on the rails and adjacent portions of the door panel. The filler strip provides an anchorage for a garnish molding frame, and has a part which coacts with the frame to provide a glass receiving channel.

It is a further object of this invention to provide a door assembly embodying the above features and having the several parts capable of being formed by relatively simple stamping operations requiring a minimum number of tools.

The foregoing as well as other objects will be made more apparent as this description proceeds, especially when considered in connection with the accompanying drawings, wherein:

15 Figure 1 is an elevational view of the inner side of a vehicle body door assembly;

Figure 2 is an edge elevational view of the door shown in Figure 1;

Figures 3 to 11 inclusive are respectively cross sectional views taken on the lines 3—3, 4—4, 5—5, 6—6, 7—7, 8—8, 9—9, 10—10 and 11—11 of Figure 1;

Figure 12 is a cross sectional view through the top of the door assembly showing the garnish molding frame and window; and

Figure 13 is a fragmentary elevational view of a modified corner construction for the door.

The door structure selected for the purpose of illustrating this invention is of the type employed on vehicle bodies, although it will be apparent from the following description that many of the features of the invention may be incorporated in the manufacture of different types of doors, such for example, as those employed in connection with refrigerator cabinets, aircraft and cooking ranges.

With the above in view, reference is made more particularly to the drawings, wherein the numeral 10 designates a vehicle body door assembly having a main panel 11 preferably formed of sheet metal and being of a design which lends itself to manufacture on a volume production basis by the use of a few relatively simple stamping operations. In the present instance the panel 11 constitutes the outer panel of the door assembly 10, and is provided with a window opening 12 in the upper portion thereof. The usual glass window 13 is provided for closing the opening 12, and provision is made for supporting the window on the panel to enable sliding movement of the window into and out of the opening 12.

The marginal edge portions of the panel 11 are turned laterally inwardly with respect to the panel to provide a flange 14 which forms the side edges of the door 10, and the inner portion of

the flange 14 is turned laterally inwardly with respect to the flange to provide a flange 15. The flange 15 coacts with the panel 11 and flange 14 to form inwardly opening generally channel-shaped top, bottom and side rails 16, 17 and 18 respectively on the panel 11. As indicated in the several cross sectional views of the drawings, the free end of the flange 15 may be turned laterally outwardly to form a stiffening flange 19. The rails or flanges noted above extend substantially continuously around the perimeter of the panel 11, and impart sufficient strength to the panel 11 to render the provision of separate pillars or frame members unnecessary.

It will further be noted from the various cross sectional views of the drawings that the edge flange 14 is drawn inwardly with respect to the side edge of the door to provide an inwardly opening channel-shaped section 20 immediately adjacent the panel 11. The inwardly opening channel-shaped section 20 extends continuously around the perimeter of the door panel 11, and the inner wall 21 of the section forms a door stop.

As shown in Figures 4, 7 and 9 of the drawings, an accessory plate 22 in the form of a sheet metal stamping is secured to the door assembly with the top edge extending along the bottom of the window opening 12. The ends of the plate are respectively secured to the flange 15 at opposite sides of the door panel 11, and the portions 23 of the flanges 15 engaged by the plate 22 are embossed laterally outwardly sufficiently to locate the inner surface of the plate 22 in a common plane with the corresponding surface of the flange 15. The bottom edge of the plate 22 is turned outwardly to form a stiffening flange 24 and the top edge of the plate 22 is turned inwardly and downwardly to form a downwardly opening channel-shaped ledge 25 at the inner side of the window opening 12, as shown in Figure 7 of the drawings. It will also be observed from Figure 7 of the drawings that the portion of the panel 11 at the bottom of the window opening 12 is turned inwardly and downwardly to form a channel-shaped ledge 26 at the outer side of the window opening 12. The ledge 26 is spaced at a somewhat higher elevation than the ledge 25, and the downwardly extending flanges of the ledges are spaced from each other sufficiently to permit free passage of the window 13 therebetween.

The size of the plate 22 is sufficient only to adequately support the various door accessories including the window regulator mechanism and latch construction. As shown in Figure 1 of the drawings, the bottom edge of the plate is spaced a considerable distance above the bottom of the door 10, and if desired a reinforcement in the form of a channel-shaped strap 27 may be provided for connecting the bottom rail portion 17 of the door to the plate 22 intermediate the ends of the latter. The outer panel 11 may further be strengthened by a gusset plate 28 of triangular configuration and secured to the lower front corner of the panel. In practice the flange 15 at the lower front corner of the panel is embossed laterally outwardly to form a seat for the gusset plate 28, and to locate the latter with the inner surface thereof flush with the corresponding surface of the flange 15.

Referring to Figures 1 and 9 of the drawings, it will be noted that the edge flange 14 at the front side of the door panel 11 is embossed inwardly at vertically spaced points to form re-

cesses 29. The recesses 29 are for the purpose of receiving hinge straps designated generally in Figure 9 by the numeral 30, and constituting part of the hinge assembly for mounting the door. In order to strengthen the front edge of the door panel 11 on which the hinges are attached, an inwardly opening channel-shaped reinforcing member 31 is provided. The reinforcing member 31 extends from a position adjacent the bottom of the door panel 11 to a position above the top recess 29 and the base of the member 31 is welded or secured to the inner side of the flange 14. Referring again to Figure 9, it will be noted that the inner flange 32 of the member 31 embraces the flange 15 on the panel, and the base of the member is embossed laterally inwardly to provide recesses 33 in positions to respectively receive the embossed portions of the adjacent flange 14. Thus it will be seen that the edge portion of the door on which the hinges are attached is reinforced to provide a strong and rigid construction.

Referring now to Figures 5, 6, and 10, it will be noted that the portion of the outer door panel 11 extending along the top and sides of the window opening 12 is turned laterally inwardly to provide a flange 34 and the free edge of the flange 34 is turned inwardly to form a flange 35. The flange 35 is spaced laterally from the flange 15 and a strip 36 is positioned between the flanges 15 and 35. The strip 36 extends along the top and sides of the window opening 12 in the outer panel 11, and is welded or otherwise permanently secured to the panel 11. The strip 36 may be fashioned from a single strip of sheet metal and bent to substantially inverted U-shaped configuration or may be formed of a plurality of sections as indicated in Figure 1 of the drawings. In either case the outer marginal edge of the strip is bent laterally inwardly to form a flange 37 which is welded or otherwise permanently secured to the inner side of the flange 35. The inner edge portion of the strip 36 is drawn laterally outwardly to provide an inwardly opening channel 38, and the inner flange 39 of the channel is turned laterally outwardly to form a flange 40. The flange 39 is welded against the outer surface of the flange 15, and the flange 40 is welded against the adjacent surface of the outwardly flange 19 on the panel 11. The part 41 of the strip at the outer side of the channel 38 is fashioned to provide a seat for engagement with the window 13, as shown particularly in Figure 12 of the drawings. It will also be noted from Figure 12 that a garnish molding frame 42 extends around the portion of the strip 36 at the inner side of the window 13, and cooperates with the seat 41 to form a channel for receiving the window 13. The garnish molding frame is removably secured in place by screws 43 which are secured to the strip 36.

It follows from the above that the strip 36 forms with the adjacent portion of the outer panel 11 a box type construction which is extremely strong and is capable of withstanding high bending or twisting stresses that may be imparted to the door. It will further be noted that by forming the outer door panel 11, side, bottom and end rails of a single piece of sheet metal, the door assembly is not only greatly simplified, but in addition, renders it possible to eliminate numerous assembly operations heretofore required in the manufacture of door structures wherein a separate frame is provided for supporting the outer door panel. In addition it

will be seen that the shape of the various parts of the outer panel is such as to enable this panel to be formed with relatively few simple stamping operations.

In Figure 13 of the drawings a modified corner construction for the door is shown. This corner construction may be employed at the corners A, B and C of the door shown in Figure 1, if desired. It will be noted that the corner shown in Figure 13 differs from the corners A, B and C in that the outer edge 50 intersects the bottom edge 51 at substantially right angles. In order to accomplish this result adjacent marginal rails of the door are notched at their juncture, and the resulting open joint is closed by welding or by covering the joint with a suitable reinforcement (not shown). The joint is indicated in Figure 13 by the numeral 52, and is not visible from the outer side of the door.

What I claim as my invention is:

1. An automobile door comprising a unitary main panel having a window opening in the upper part thereof, and having peripheral flanges extending completely around said panel, said flanges comprising a first flange extending generally at right angles to the adjacent portions of said panel, a second flange extending inwardly of the edge of the door from the edge of said first flange, said second flange being generally parallel to and spaced from the adjacent portions of said panel, said second flange constituting a door stop and said first flange constituting a stiffening flange therefor, a third flange extending outwardly of the panel from the inner edge of said second flange, a fourth flange extending inwardly of the edge of the door from the edge of said third flange, said fourth flange being generally parallel to and spaced from the adjacent portions of said panel, said fourth flange extending across said main panel directly below the window opening therein, the ends of said plate being secured to said fourth flange at opposite sides of said main panel, the upper edge of said plate being spaced from the portion of said main panel at the bottom of the window opening therein to provide for passage of a movable window glass, and strip material connecting the portions of said fourth flange adjacent the top and sides of said window opening to the adjacent portion of the main panel.

2. An automobile door comprising a unitary main panel having a window opening in the 50

upper part thereof, and having peripheral flanges extending completely around said panel, said flanges comprising a first flange extending generally at right angles to the adjacent portions of said panel, a second flange extending inwardly of the edge of the door from the edge of said first flange, said second flange being generally parallel to and spaced from the adjacent portions of said panel, said second flange constituting a door stop and said first flange constituting a stiffening flange therefor, a third flange extending outwardly of the panel from the inner edge of said second flange, a fourth flange extending inwardly of the edge of the door from the edge of said third flange, a plate extending across said main panel directly below the window opening therein, the ends of said plate being secured to said fourth flange at opposite sides of said main panel, the lower edge of said plate being spaced substantially upwardly from the lower edge of said panel, and a brace connecting the mid-portion of said plate to the fourth flange at the bottom of said main panel, the upper edge of said plate being spaced from the portion of said main panel at the bottom of the window opening therein to provide for passage of a movable window glass, and strip material connecting the portions of said fourth flange adjacent the top and sides of said window opening to the adjacent portion of the main panel.

AUGUST L. NELSON.
